SLEEPING GARMENT

Walter J. Munro, Scarsdale, N. Y.

Application May 16, 1936, Serial No. 80,113.

5 Claims. (Cl. 5—343)

This invention relates to improvements in sleeping garments and it pertains particularly to sanitary sleeping robes for infants, providing a maximum of comfort and protection.

5 Various forms of sleeping robes for infants have heretofore been devised, but many of the types previously known have frequently been unsatisfactory because of lack of complete comfort for the infant or because of their failure to insure at 10 the same time adequate covering for the infant, complete freedom of movement, sufficient circulation of air within the garment, etc.

It is an object of the present invention to provide a new and improved sleeping garment, particularly designed for infants.

20 A further object of the invention relates to infants' sleeping garments providing complete comfort and sanitation, ample space to permit free movement of the infant's arms, legs and body 20 while at the same time maintaining the infant adequately covered.

Other objects of the invention will appear hereinafter.

A preferred form of garment is illustrated in 25 the drawing in which:

Figure 1 illustrates the sleeping garment in open position, and fastened to a crib or bed, and

Figure 2 shows the garment after the infant is placed therein and the garment fastened in position.

30 Referring to the drawing, the garment comprises a back panel 10, preferably extending the full length and width of the garment, to which is attached an upper front panel 11 which is attached at its top and side edges to panel 10, thereby permitting free motion of the infant's arms between the panels 10 and 11 and under the infant's head. A neck opening 12 which may be provided with a suitable soft binding tape 13 is 35 located in the front panel at a point sufficiently below the top edge of panel 11 to allow the infant's head to rest on the panel 11 while permitting the infant to stretch its arms under panel 11 and to cross its hands and arms under 40 its head without being uncovered.

45 Panel 11 is divided from the opening 12, preferably down to its bottom edge 14 to permit the infant to be inserted into the garment, the portions 15 and 16 adapted to be closed by snap fasteners 17 and 18, or other suitable fastening devices, so as to hold the infant in place and to cover at least the upper portion of the infant's body from its neck downwardly.

50 Along the side edges and bottom edges of the back panel 10 are attached covering panels 19 and

20 adapted to be detachably secured along their inner edges by suitable fasteners, for example, interlocking members 21, adapted to be detachably drawn together by cam bail 23 so as to fasten the panels 19 and 20 together at their meeting 5 edges.

Overlapping panels 16 and 19 may be extended so as to overlap panels 15 and 20 respectively whereby to cover the fastening devices 21 and fasteners 17 and 18, if desired.

10 When the sleeping robe is completely secured about the infant, the panels 19 and 20 overlap the panel 11 above the upper portion of the infant's body, thereby providing a double blanket covering while allowing the infant free movement between panel 11 and panels 19 and 20.

15 Fastening tapes 23', 24, 25 and 26 are attached to the sleeping garment, preferably at the meeting edges of the front and back panels, for attaching the garment to a bed or the like (as shown in Figure 1) and thus insuring that the garment will be maintained in proper position.

When it is desired to place the infant in position in the garment, fasteners 17 and 18 and also fasteners 21 are disengaged, thereby permitting 25 the infant to be readily placed in the garment. Fasteners 17, 18, and 21 are then fastened in closed position, leaving the infant's head free to move on panel 11 and permitting free movement 30 of the infant's arms in all directions while maintaining them completely covered. Due to freedom of movement between panel 11 and panels 19 and 20, the infant can kick or raise his feet and legs freely, while at the same time air is circulated into and within the robe by passage of the 35 air between the panels 11 and 19 and 20, by virtue of the relative movement of panels 19 and 20 with respect to panel 11, providing at the same time adequate covering for every portion of the infant's body.

40 It will be understood that slits may be provided at opposite sides of the neck opening 12 to permit the infant to extend its arms therethrough to grasp a bottle, toys, etc., the said slits being provided with detachable fastening devices and/or an overlapping element to overlie the slits, if desired.

45 It will further be understood that the garment may be provided with a sanitary lining adapted 50 to be positioned under the infant, if desired.

In addition, the back panel may be made completely detachable from the front panels by means of detachable fasteners, although it is preferred that the panels be permanently stitched 55

or otherwise permanently secured together along the edges of the back panel.

While the invention has been described with respect to one preferred embodiment, it will be understood that the invention is susceptible of considerable modification as to various details without departing from the spirit thereof.

I claim:

1. A robe adapted for use as a sleeping garment for infants comprising a back panel, an upper front panel attached at its upper and side edges to said back panel and provided with an opening positioned substantially below its upper edge, said front panel being divided along a line extending 15 downwardly from said opening to form edges provided with detachable fastening means, said upper front panel furthermore extending downwardly a sufficient distance to cover a substantial portion of the child's body, a lower front panel 20 attached at its lower and side edges to the back panel and being free to move relative to said upper front panel, said lower front panel being divided along a line extending downwardly from its upper edge to form edges provided with detachable fastening means, said lower front panel overlapping said upper front panel when fastened in position 25 whereby to provide adequate covering for the infant while permitting freedom of movement.
2. A robe adapted for use as a sleeping garment for infants comprising a back panel, an upper front panel attached to said back panel and provided with an opening positioned substantially below its upper edge, said opening being provided 30 with detachable fastening means for permitting an infant to be readily placed in position in the robe and for securing said infant, said upper front panel extending downwardly a sufficient distance to cover a substantial portion of the child's body, a lower front panel attached to said back 35 panel and being free to move relative to said upper panel, said lower front panel overlapping said upper front panel when an infant is in covered position whereby to provide adequate covering

for the infant while permitting freedom of movement.

3. A robe adapted for use as a sleeping garment for infants comprising a back panel, an upper front panel attached to said back panel and provided with an opening for permitting an infant to be inserted into the robe, said upper front panel extending downwardly a sufficient distance to cover a substantial portion of the child's body, a lower front panel attached to said back panel 10 and being free to move relative to said upper front panel, said lower front panel overlapping said upper front panel when an infant is in covered position whereby to provide adequate covering 15 for the infant while permitting freedom of movement.

4. A robe adapted for use as a sleeping garment for infants comprising a back panel, an upper front panel attached to said back panel and provided with a neck opening, said upper front panel 20 extending downwardly a sufficient distance to cover a substantial portion of the child's body, a lower front panel secured to said robe and being free to move relative to said upper front panel, said lower front panel overlapping said upper 25 front panel when an infant is in covered position whereby to provide adequate covering for the infant while permitting freedom of movement.

5. A robe adapted for use as a sleeping garment for infants, comprising upper and lower front 30 panels attached to each other, said upper front panel having a neck opening and extending downwardly a sufficient distance to cover a substantial portion of the child's body, said lower front panel overlapping said upper front panel and being 35 adapted to move relative to said upper front panel along a substantial portion of its width when the robe is in closed position over the infant whereby to permit free movement of the infant's body while providing adequate covering and circulation of air into and out of said robe between said 40 upper and lower members.

WALTER J. MUNRO.
